UNITED STATES PATENT OFFICE.

ALONZO GRAFFAM, OF DEKALB, ILLINOIS, ASSIGNOR TO ARTHUR G. LEONARD, TRUSTEE, OF CHICAGO, ILLINOIS.

PEGGING-MACHINE.

SPECIFICATION forming part of Letters Patent No. 698,700, dated April 29, 1902.

Application filed May 22, 1896. Serial No. 592,648. (No model.)

To all whom it may concern:

Be it known that I, ALONZO GRAFFAM, a citizen of the United States, residing at De-
kalb, in the county of Dekalb and State of
Illinois, have invented a certain new and use-
ful Improvement in Pegging-Machines, which
is fully set forth in the following specifica-
tion, reference being had to the accompan-
ying drawings, in which—

10 Figure 1 is a front elevation of the pegging-
machine as a whole. Fig. 2 is a side eleva-
tion thereof. Fig. 3 is a detail view, partly
in vertical section and partly in elevation, of
the horn-post, horn, and anvil. Fig. 4 is a
15 plan view of the anvil. Fig. 5 is a vertical
section on the line 5-5 of Fig. 4. Fig. 6 is a
detail view of the cam and bell-crank lever,
which actuate the horn-post. Fig. 7 is a de-
tail elevation of the pedal and spring device
20 attached to the lower portion of the horn-post.
Fig. 8 is a vertical section of a shoe which has
just been pegged.

It has heretofore been common during the
operation of pegging shoes, to secure the out-
25 sole to the upper and the insole in pegged
shoes, to leave the last in the shoe. The shoe
was held on a pegging-jack, which pressed the
sole up firmly against the pegging mech-
anism when the peg was driven. As wooden
30 pegs cannot be inserted without the aid of a
puncturing instrument, which makes a hole
through the entire material resting upon the
last, and as the thickness of the material var-
ies at different parts of the sole, it is obvious
35 that the awl, which must be longer than the
thickest part of the sole, will pass into the
last more or less where the sole is thinner, as
in the shank particularly. Inasmuch as it is
also impracticable to use more than one width
40 of the wooden strip from which the pegs are
cut just before being driven and inasmuch as
the pegs must be sufficiently long to bring
their points at least flush with the inner sur-
face of the sole at all points, it is apparent
45 that over the thinner portions of the sole the
points of the pegs will project beyond the in-
ner surface thereof, and will thus be driven
more or less into the last. This constant
pricking of the last by the awl and the driv-
50 ing of pegs thereinto soon deteriorates it and
in a short time renders it useless, causing

great expense to the manufacturer in renew-
ing his supply of lasts. Moreover, the use of
the last is the source of frequent breakage of
awls and other parts, and the cost of the labor
employed in drawing the last from the shoe
after it has been fastened to the inner sole by
perhaps a hundred pegs projecting into the
surface thereof is very considerable. To avoid
these sources of loss and diminish the cost of
pegging and the labor requisite thereto, I
have devised a machine in which a slotted
anvil is constantly presented to the inner sur-
face of the insole just beneath that point
where the puncturing and hammering mech-
anism of the machine is at work upon the out-
sole.

While I find that the broad idea of a slotted
anvil into which the awl passes in punctur-
ing the sole and which it traverses in feeding
the sole is not novel, yet certain details and
features of the construction whereby such an
anvil is made practical are novel with me, and
my invention pertains to these details and
features.

In the pegging-machines heretofore pro-
posed, in which the work was to be pegged on
a horn after the last is drawn, the awl of the
peg-driving mechanism was to enter the ma-
terial in line with the center of the horn-tip
or in the axis of rotation of the horn, and af-
ter the awl-hole was made the material was
to be fed the distance between two adjacent
pegs, thus bringing the part of the material
that was to receive the peg at a distance
radially from the axis of the horn equal to the
length of the feed. Thus the work was to be
pierced by the awl at a point coaxial with the
horn; and the peg was to be driven at a point
non-coincident with the axis of the horn, re-
quiring that the tip or substantially circular
anvil in the end of the horn should be of a
radius substantially greater than the length
of the feed, thereby precluding the entrance
of the horn far enough into the toe portion
of the shoe to drive the pegs properly.

In the work-support forming the subject of
this invention the work-supporting anvil,
which is supported in the end of the horn, but
restrained from rotation therewith with rela-
tion to the peg-driving mechanism, is provided
with an awl-passage extending vertically into

the same, but having its operative portion—*i.e.*, the part through which the awl passes during its feeding movement—with its ends non-coincident with the axis, being set to one side 5 of the axis a distance about equal to one-half the normal feed or space between the consecutive pegs to be driven in the material. The awl-hole is thus formed in the material at a point non-coincident with the axis of the 10 horn, and the feed takes place, carrying said material so that the awl-hole formed therein passes across the center of the horn and at the end of the feed movement is non-coincident therewith on the other side of the axis 15 from the point at which the awl-hole was made, so that the diameter instead of the radius of the button, as heretofore, need be only large enough to accommodate the feed of the material and afford a support therefor adjacent 20 to the point in the material at which the awl penetrates and at which the peg is driven. Thus, other things being equal, the button having an awl-passage with its operative portion beginning and ending non-coincidently 25 with the axis of the horn in accordance with the present invention may be much smaller than those heretofore made having a concentric awl-passage, and by this feature of construction the horn-tip and work-support forming the subject of the present invention may 30 be made sufficiently small to peg properly in any required portion of a boot or shoe.

In a machine having an awl-feed, in which my present invention is shown as embodied, 35 I make the slot in the anvil of a sufficient depth to accommodate the awl and pegs, and while the non-coincident location of the ends of the operative portion of my slot would be embodied in a slot which began at one side 40 of the center of the axis of the horn and terminated at the other side of said axis, yet I preferably continue said slot in both directions from the center, so that it forms a channel completely through the anvil, thus permitting 45 the pegs to pass freely out of one end of the slot after being pegged, and if it is desired to retrace any portion the slot being open at both ends readily permits this.

Referring to the drawings by letter, A represents 50 the main frame of my pegging-machine. B B' are the loose and driving pulleys, and C the balance-wheel, mounted upon and adapted to revolve the shaft D. E is a spring device adapted to actuate the pegging mechanism. F is the guide or gage against which the edge of the sole bears while being pegged. G represents the awl, and H the hammering mechanism. These parts are all of any preferred construction, and being well known in 55 the art require no further description here.

The shaft D carries a cam-surface I, upon which travels a roller J, carried upon one arm of the bell-crank lever J', to the other arm of which is pivoted the upper end of the connecting-rod K. The lower end of the rod K 60 is pivotally connected to one end of the pedal-lever L, pivoted as at l. The other end of the

pedal-lever L is provided with a pedal L'. Midway between the pedal L' and the pivotal mounting of the lever at l there is pivotally attached to the said lever, as at l², the lower end of the horn-post, later described.

The frame A is provided with two superimposed horizontal brackets A' and A². The vertical horn-post M is loosely mounted in the 70 said brackets, so as to be free to move vertically therein, the said brackets forming guides for such movement. The lower portion of the horn-post is reduced in section to form a shank M', and the upper end of this shank M' 80 is screw-threaded, as at m. Upon this screw-threaded part is mounted a collar m', which can thus be vertically adjusted upon the shank. The lower of the two brackets A' is provided with the stay-rods N, depending 85 therefrom, which support at their lower ends a collar N', surrounding the horn-post, which is free to move vertically therein. Between the collar m' and the collar N' and surrounding the shank of the horn-post is mounted a 90 compression-spring O. The lower end of the shank M' is pivotally connected to the pedal-lever at l², as hereinabove described.

Upon the upper portion M² of the horn-post M is mounted the sleeve P, resting upon the 95 flange m² and adapted to rotate loosely upon the horn-post. The sleeve P is provided with the bracket projection P', in which is rigidly mounted the horn Q. The horn Q terminates in the inclined branch Q', so disposed as to 100 bring the end of the said branch vertically above the center of the horn-post itself. In the extremity of the said branch Q' is mounted the vertical pivot R, which carries at its upper end the slotted anvil S, which is preferably formed of the base portion S' and the two vertical walls or flanges S², forming an intermediate space or slot S³. To the lower end of the pivot R is secured the small bevel-pinion T, meshing with the pinion T', carried 105 upon the shaft T², which is mounted in bearings upon the branch Q'. The lower end of the shaft T² is connected with a vertical shaft U, mounted in brackets attached to the horn Q through the universal joint U'. The lower 110 end of the shaft U is provided with a small bevel-pinion u', which through the intermediate bevel-pinions u² and u³ meshes with the bevel-gear V, which is rigidly secured upon the extreme upper end of the horn-post M. 115

For the purpose of throwing the machine into and out of operation I employ any suitable form of clutch mechanism Y, operated by a pedal-lever Y', with which it is connected in any suitable manner. The operation of 120 these parts in connection with the pegging of a shoe is as follows: The shoe is first lasted, the outer sole temporarily tacked in place, then the last is withdrawn. The shoe is then placed upon the horn in such wise that the 125 slotted anvil bears against the inner surface of the sole at the point where it is desired to drive the first peg. The machine is then started into operation by the pedal-and-clutch

mechanism described. The awl descends, punctures the sole, and as it rises feeds the shoe forward, so that the hole thus made is brought under the peg and peg-driving mechanism. As seen in Fig. 1, the awl as it descends is non-coincident with the axis of rotation of the horn, and as it feeds it crosses said axis, so that when it rises it is non-coincident on the other side. As the ends of the pegs X X thus come through the inner surface of the sole they form a row of projections which pass rearwardly through the slot in the anvil as the shoe is fed forward. The anvil is kept in the same position relative to the machine as a whole and to the pegging mechanism by means of the gearing T T', &c., hereinabove described. When the horn is rotated to change the direction of the pegging with reference to the sole of the shoe, the anvil, although it rotates on the horn, retains the same position with regard to the rest of the machine, so that the pegs still may pass rearwardly out of the slot.

It is not necessary to have the slot extend completely through the anvil. If it extends from the point at which the awl and peg enter the slot to the point at which the peg ends pass out of the slot rearwardly, the device is operative for most purposes. It is preferable, however, to have the slot extend completely through the anvil, as it is frequently desirable to retrace the anvil's path along the inside of the sole in order to repeg portions where there has been some defect in the first pegging. This could not be done if only one end of the slot were closed.

The cam I, through its connections with the horn-post, intermittently releases the upward pressure upon the said post each time that the shoe is fed forward and materially facilitates the feeding process. The spring device used in connection therewith holds the anvil and shoe firmly up to their work and yet at the same time yieldingly, so as to take off much of the jar from the driving of the pegs.

When the pedal L' is depressed by the foot, the horn is thrown still farther down and the shoe may be removed, the spring again retaining the anvil and horn to their normal positions.

I do not limit myself to the specific devices shown and described, which may be modified in many details without departing from the principles of my invention; nor do I restrict my invention to a combination of all the features thereof; but

What I claim, and desire to secure by Letters Patent, is—

1. In a pegging-machine, the combination of peg cutting, driving and feeding mechanism; a rotating horn carrying an anvil, the said anvil being provided with a slot extending wholly across the same; and means adapted to retain the slot in proper direction to the line of pegs, and the feeding of the shoe, notwithstanding the rotation of said horn on its

axis in pegging the shoe, substantially as, and for the purposes, set forth.

2. In a pegging-machine, the combination with peg cutting, driving and feeding mechanism; of a rotatable horn carrying an anvil, the said anvil being provided with a slot extending wholly across the same and in the direction of the feeding movement of the shoe; and connections between the said anvil and a non-rotating portion of said machine, whereby the relative fixed position of the machine and anvil is maintained, despite the rotation of the horn, substantially as described.

3. The combination of the rotatable horn of a pegging-machine, with the awl arranged non-coincident with the axis of rotation of the horn, said awl having a feed movement from one to the other side of and through the axis of the horn, substantially as described.

4. The combination of the rotatable horn of a pegging-machine, with a work-supporting anvil pivotally supported in the tip thereof and provided with an awl-passage having both the ends of its operative portion non-coincident with the axis of rotation of the horn and means for preventing rotation of the anvil when the horn is turned, substantially as described.

5. The combination of the rotatable horn of a pegging-machine, with a work-supporting anvil pivotally supported in the tip thereof and provided with an awl-passage having both the ends of its operative portion non-coincident with the axis of rotation of the horn, the non-rotatable but vertically-movable treadle-rod or horn-post passing through said horn, and connections between the anvil and the upper end of said treadle-rod for preventing the rotation of the anvil when the horn is turned, substantially as described.

6. The combination of the rotatable horn of a pegging-machine, with a work-supporting anvil pivotally supported in the tip thereof and provided with an awl-passage having both the ends of its operative portion non-coincident with the axis of rotation of the horn, the non-rotatable but vertically-movable treadle-rod or horn-post passing through said horn, a treadle connected to said treadle-rod, and connections between the anvil and the upper end of said treadle-rod for preventing rotation of the anvil when the horn is turned, substantially as described.

7. The combination of the rotatable horn of a pegging-machine, consisting of the sleeve, the substantially vertical portion, and the inclined portion, with a work-supporting anvil pivotally supported in the tip thereof and provided with an awl-passage having both the ends of its operative portion non-coincident with the axis of rotation of the horn, the non-rotatable but vertically-movable treadle-rod or horn-post passing through said horn, and connections between said treadle-rod and anvil comprising the gears on the anvil and the end of the treadle-rod, and the rods U and T' geared thereto, for preventing the ro-

tation of the anvil when the horn is turned, substantially as shown and described.

8. In a pegging-machine, the combination of a rotatable horn, with the work-supporting anvil pivotally supported in the tip thereof and provided with an awl-passage having both the ends of its operative portion non-coincident with the axis of rotation of the horn, and peg cutting, driving and feeding mechanism, 10 the awl of said mechanism being arranged non-coincident with the axis of rotation of said horn, and having a feed movement from one to the other side of the axis of the horn, substantially as described.
- 15 9. In a pegging-machine, the combination of the rotatable horn, with the work-support-

ing anvil pivotally supported in the tip thereof and provided with an awl-passage having both the ends of its operative portion non-coincident with the axis of rotation of the horn, 20 means for preventing rotation of the anvil when the horn is turned, and peg cutting, driving and feeding mechanism, the awl of said mechanism being arranged non-coincident with the axis of rotation of said horn, 25 and having a feed movement from one to the other side of the axis of the horn, substantially as described.
